UNITED STATES PATENT OFFICE

161,007

AUDIBLE SIGNAL DEVICE

Samuel M. Dover, Chicago, Ill.

Application August 23, 1949, Serial No. 4,650

Term of patent 14 years

(Cl. D72—1)

To all whom it may concern:

Be it known that I, Samuel M. Dover, a citizen of the United States, a resident of Chicago, Illinois, have invented a new, original, and ornamental Design for an Audible Signal Device, of which the following is a specification, reference being had to the accompanying drawing, forming a part hereof.

In the drawing:

Figure 1 is a side elevational view of an audible signal device, showing my new design;

Figure 2 is a front elevational view thereof; and

Figure 3 is a bottom plan view thereof.

I claim:

The ornamental design for an audible signal device, substantially as shown.

SAMUEL M. DOVER.
